DESIGN FOR A SAFETY BATHTUB

Louis K. Vaughan, Woodland, Calif.

Application April 24, 1937, Serial No. 68,962

Term of patent 14 years

To all whom it may concern:

Be it known that I, Louis K. Vaughan, a citizen of the United States, residing at Woodland, in the county of Yolo and State of California, have invented a new, original, and ornamental Design for a Safety Bathtub, of which the following is a specification, reference being had to the accompanying drawing, forming a part thereof.

In the drawing:

Figure 1 is a perspective view of a safety bathtub, Figure 2 is a top plan view of the same, and Figure 3 is a sectional elevation of the safety bathtub; all views showing my new design.

I claim:

The ornamental design for a safety bathtub, as shown.

LOUIS K. VAUGHAN.
